(57) CLAIM

The ornamental design for a display screen with animated graphical user interface as shown and described.

DESCRIPTION

FIG. 1 is a front view of a first image in a sequence for a display screen with animated graphical user interface showing our new design;

FIG. 2 is a second image thereof; and,

FIG. 3 is an enlarged view of the encircled portion labeled as '3' in FIG. 2, shown separately for completeness of illustration.

The peripheral dash-dot-dash lines illustrate a display screen or portion thereof and form no part of the claimed design. The dash-dot-dot-dash broken lines in FIG. 2 illustrate the perimeter of a portion of the graphical user interface that is shown enlarged in FIG. 3 and form no part of the claimed design. The remaining broken lines illustrate features that form no part of the claimed design. The appearance of the animated graphical user interface sequentially transitions between the images shown in FIGS. 1-2. The process or period in which one image transitions to another forms no part of the claimed design.
